IRVING R. SMITH, OF MILWAUKEE, WISCONSIN, ASSIGNOR TO STERLING WHEEL-BARROW COMPANY, OF MILWAUKEE, WISCONSIN, A CORPORATION OF WISCONSIN.

FOUNDRY-FLASK.

1,113,500.

Specification of Letters Patent. Patented Oct. 13, 1914.

Application filed February 18, 1912. Serial No. 678,966.

To all whom it may concern:

Be it known that I, IRVING R. SMITH, a citizen of the United States, residing at Milwaukee, in the county of Milwaukee and State of Wisconsin, have invented a new and useful Improvement in Foundry-Flasks, of which the following is a specification.

My invention relates to improvements in foundry flasks made of wrought metal and the objects of my invention are to strengthen the wrought metal against torsion and bending without unduly adding to the weight of medium sized flasks, and to utilize the strengthening means as a material addition to the handiness of the flask. These objects are accomplished by the constructions shown in the accompanying drawing which forms a part of this specification, and in which—

20 Figure 1 shows a plan view of a foundry flask embodying my invention. Fig. 2 shows an end view of the flask partly in vertical section. Fig. 3 shows a modified form of the section of the flask with the same 25 strengthening device shown in Fig. 2. Fig. 4 shows a plan view with a modified form of the strengthening device and Fig. 5 shows a vertical cross section through Fig. 4.

That flasks for use in iron and steel foundries should be made of metal is unquestionable owing to the burning gases and molten metal in connection with their employment. The general use of metal flasks has heretofore been precluded by their excessive 25 weight, and I have found this excessive weight is due to the improper distribution of the metal in flasks as heretofore constructed in relation to the forces to be resisted.

40 In general terms, I construct my flask with vertical walls formed of a relatively thin sheet of metal having sufficient lateral strength for sand holding purposes, and surround these walls at about the middle of 45 their height by a single bar of metal of sufficient strength to withstand all the torsional and lateral bending strains to which the flask is ordinarily subjected.

The flask as shown in Figs. 1 and 2 consists of a strip of rolled steel which is cut the proper length and bent to the requisite form. The guide pin plates (a) are then riveted on, one of them covering the joint at the ends of the strip. The inturned flanges (f) are merely for the purpose of lifting the

sand. At the middle of the height of the flask a rib (b) is rolled on the metal strip to resist the torsional strains and to resist lateral bending in small flasks. In medium sized flasks, such as are generally handled by two men when lifting off or on, additional hand holds are necessary, and if the length of the flask is considerable additional reinforcement against torsion and bending is needed. To answer these requirements a reinforcing strip is rolled, of steel preferably, which strip has a semi-circular bead (c) provided with flanges (e e) in the same plane and a flange (g) perpendicular to (e e). Pieces of this strip are cut off of sufficient length to reach around one side of the flask from one guide pin plate (a) to the other. These pieces are bent to fit the corners of the flask, and are riveted to the walls of the flask through the flanges (e e). The flange (g) affords a hand hold all around the flask or a means for the crane hooks to take hold of. But its essential and most important feature is to form a torsion and bending resisting bar of the same kind as the bead (b). All torsional and bending strains occurring anywhere in the height of the flask are effectively referred to this bar and still the major portion of the vertical wall of the flask is only of sufficient thickness for sand holding purposes. This bar also materially strengthens the corners of the flask. As shown in Fig. 3, this bar may be applied to a plain section of metal and will be just as effective in resisting torsion and bending as it is in Fig. 2. This is of great importance as the sizes and relative proportions of flasks is almost infinite and one size of reinforcement will answer for a wide range of flasks, whereas it would be practically impossible to make special rolls for all sizes.

In Figs. 4 and 5, a reinforce and hand hold is shown consisting of a piece of pipe (h) secured to the flask by clips (k). Blocks (l) affording seats for the pipe may be supplied or omitted. This pipe attachment forms a very convenient hand hold, a strong reinforcement against lateral bending and will assist to some extent in resisting torsion.

Having now fully described my invention in certain forms which it may take what I claim as my invention is:

1. A foundry flask formed of rolled metal,

having guide pin plates at its opposite ends and having reinforcing bars attached on the outside of the flask at the middle of its height extending from one guide pin plate 5 to the other.

2. A foundry flask formed of rolled metal, having guide pin plates at its opposite ends and having reinforcing bars attached on the outside of the flask at the middle of its 10 height extending from one guide pin plate to the other, said bars having projections for attaching them to the flask, and being provided with a relatively wide projecting flange forming a hand hold.

3. A foundry flask formed of rolled metal, 15 having guide pin plates at its opposite ends, and having reinforcing bars attached on the outside of the flask at the middle of its height extending from one guide pin plate to the other, said bars consisting of a curved 20 hollow central portion disposed with its hollow side toward the flask, and flanges on each side of said curved portion by which the bar is attached to the flask.

IRVING R. SMITH.
